UNITED STATES PATENT OFFICE.

SIDNEY JAMES WILLIAMS, OF KENSINGTON, LONDON, ENGLAND.

IGNITION APPARATUS FOR USE WITH INTERNAL-COMBUSTION ENGINES.

1,269,889.

Specification of Letters Patent. Patented June 18, 1918.

Application filed June 12, 1916. Serial No. 103,138.

To all whom it may concern:

Be it known that I, SIDNEY JAMES WILLIAMS, a subject of the United Kingdom of Great Britain and Ireland, residing at No. 5 83 Abingdon Villas, Kensington, in the county of London, England, have invented new and useful Improvements in or Relating to Ignition Apparatus for Use with Internal-Combustion Engines, of which the following is a specification.

This invention relates to ignition apparatus for use with internal combustion engines and is particularly applicable for use with motor cars.

15 The object of the invention is to avoid the use of a magneto-generator; to increase the efficiency of the motor-starter; and to reduce the cost of manufacture.

According to my invention I use a non-trembler coil with a contact breaker, a high tension distributor and two condensers, to take the place of the magneto-generator and in order to enable an internal combustion engine to be started I use a trembler in 20 parallel with the non-trembler induction coil. Between the earth lines of the non-trembler coil and the trembler I introduce an additional earth line for the purpose of completing a circuit at starting through the two primary windings of the trembler and non-trembler coil, in spite of the fact that the contact-breaker may be open, so that immediately a stud, or button, on the additional earth line, is depressed and the circuit 25 completed, sparking takes place in the cylinder and continues until the stud is released, when the trembler is cut out of circuit, which is completed through the non-trembler coil and the contact breaker operated from the valve shaft.

In the accompanying drawings is illustrated a method of carrying the invention into practical effect.

A is the battery, or other source of electric energy, B is the low tension or primary coil for operating the trembler coil, C being the non-trembler. D is the condenser used in conjunction with the trembler coil B. D' is the condenser used in conjunction with the 30 non-trembler coil C. F is the trembler and F' the bridge for same, operating in conjunction with the coil B and the non-trembler coil C. I is the contact breaker operated from the valve shaft, or other suitable part of the engine. A distributor R, operated in a similar manner to the contact

breaker I, connects the source of electric energy with the sparking plugs, each in the order in which it is desired the spark should take place. L is the push button to enable 60 the additional earth line M to be brought into operation when it is desired to start the engine.

The *modus operandi* is as follows:

When the button L is depressed the current from the battery A passes through the primary windings of the coil B and the trembler mechanism F, F', causing the current to flow through both the trembler and non-trembler coils C although the contact 65 breaker I, which is operated from the valve shaft, may be open. One end of the primary winding of each coil is connected in parallel at F' to the bridge piece. The additional earth line M having the push button 70 L is connected across the earth of the coil B and non-trembler coils C when the push button is depressed.

If it be required to start the engine, although the contact breaker circuits be open, 80 by depressing the push button L the circuit is connected to earth through the additional earth line M, enabling the current to pass from the coil B and non-trembler coil C to earth, thereby inducing the required current 85 in the secondary windings of the non-trembler coil C. The button L may then be released and the non-trembler coil C will come into operation through the contact breaker I, enabling the correct sparking to take place 90 in the cylinders.

By the use of apparatus as above the cost of construction is considerably reduced; the starting of the engine may be effected without the necessity of using the ordinary starting gear; and the efficiency of the ignition device is increased, augmented induction arising in the non-trembler coil C as a consequence of the additional iron in the same field produced by the core in the primary 100 coil B.

I claim:

1. An ignition apparatus for internal combustion engines, comprising a source of electric energy, a trembler, a primary coil in 105 parallel with a non-trembler coil, a high tension distributor, two condensers one connected to the primary coil and one to the non-trembler coil, a contact breaker connected to the valve shaft, in combination 110 with an additional earth line between the earth lines of the two coils, and a depression

stud on said additional earth line, substantially as described.

2. An ignition apparatus for internal combustion engines, comprising, in combination, a source of electric energy, a vibrator, an actuating coil for the vibrator adapted to be energized by current from said source, a transformer the primary coil of which is in parallel with the vibrator actuating coil, two earth lines one leading from the transformer primary coil and the other from the vibrator actuating coil, a distributor interposed in the earth line of the transformer primary coil, two condensers one connected to the vibrator actuating coil and the other connected to the

transformer primary coil, a contact breaker for opening and closing the circuit through the vibrator actuating coil and adapted to be operated by a moving part of the engine, 20 a normally open additional earth line between the two earth lines first-mentioned, and a manually operable circuit closing device for closing the additional earth line at will, substantially as described. 25

In testimony whereof I have signed my name to this specification in the presence of two subscribing witnesses.

SIDNEY JAMES WILLIAMS.
